UNITED STATES PATENT OFFICE

121,866

DESIGN FOR A TWINE HOLDER

Charles N. Colstad, Attleboro, Mass.

Application April 8, 1940, Serial No. 91,543

Term of patent 7 years

To all whom it may concern:

Be it known that I, Charles N. Colstad, a citizen of the United States, residing at Attleboro, in the county of Bristol and State of Massachusetts, have invented a new, original, and ornamental Design for Twine Holders, of which the following is a specification, reference being had to the accompanying drawing, forming part thereof.

Fig. 1 is a side elevational view of the twine holder, showing the hemispherical shells in their closed or edge interfitting positions,

Fig. 2 is an angularly directed side view of the twine holder as seen when viewed along the line indicated by the arrow A in Fig. 1, and,

Fig. 3 is a sectional view through the container elements of the twine holder, taken along the line 3—3 of Fig. 1.

I claim:

The ornamental design for a twine holder, substantially as shown and described.

CHARLES N. COLSTAD.
